H. LINDENSMITH

FENCE POST

Filed March 17, 1926

Patented Apr. 24, 1928.

1,667,424

UNITED STATES PATENT OFFICE.

HARRY LINDENSMITH, OF WALKERTON, ONTARIO, CANADA.

FENCEPOST.

Application filed March 17, 1926. Serial No. 95,439.

My present invention appertains generally to improvements in the art of fences, and specifically to a fence post construction, as described in the present specification and illustrated in the accompanying drawings.

It includes, preferably a post having dual parallel flanges, conveniently in the form of a channel, through which tension pins are extended in spaced relation corresponding with the wires of a fence, the latter extending through said tension pins so that they may be tightened upon rotation of said tension pins by winding thereabout.

More specifically, this fence post is particularly adapted for a corner post, or may be used at spaced locations in a fence, and provides in all its adaptions simple and efficient means whereby the wires of a fence may at all times be adequately supported and kept taut.

The tension pins aforesaid are provided with square or polygonal shaped shoulders which seat in like-shaped apertures in a flange of the fence post so that when the wires of the fence are tightened by turning said tension pins through which they extend, the tension pins may be adjusted to seat the shoulders thereof in said apertures and thus lock the same from turning.

Other objects and advantages of the invention will become apparent ensuing a perusal of the following description read in conjunction with the annexed drawings, in which:

Fig. 1 is a fragmentary elevation illustrating a portion of a fence post constructed in accordance with an acceptable embodiment of my invention.

Fig. 2 is a transverse vertical section as it would appear when taken on the plane designated by the line 2—2 on Fig. 1.

Fig. 3 is a corresponding view showing the wires of the fence wound about the tension pins of the post.

Like numerals of reference designate corresponding parts throughout the different views.

The character A generally designates the fence post, which as promised, may be of any standard shape such as an angle, I H or any channel section which is provided with dual parallel flanges. Since the latter form is more particularly adapted for my present invention, I have shown the same, the numeral 4 designating the web thereof and the numerals 5 and 6 the flanges.

The flange 6 is perforated in spaced relation with circular apertures or annular openings 7. The other flange is perforated in corresponding spaced relation with square, or permissibly polygonal, apertures 8.

Tension pins 9 are extended through said apertures in said flanges for fence wire retaining purposes. Each tension pin 9 includes a square head 10 integral with a like-shaped shoulder 11, which corresponds in size with the square apertures 8. The remainder of the tension pin is round, the diameter thereof being slightly less than the diameter of the apertures 7. Holes 12 and 13 are drilled through the ends of the tension pins to receive cotter pins 14.

In Fig. 1, I have shown the two lower tension pins in locked position. It is obvious from this figure that the square shoulders 11 thereof are seated in the square apertures 8, while the cotter pins 14 are extended through the holes 12 to retain these tension pins in locked position. To tighten the wires 15 of the fence, which extend through the hole 16 in each tension pin 9, it is merely necessary to withdraw the cotter pins 14 from the holes 12 and then withdraw the tension pins a sufficient distance to disengage the square shoulders 11 thereof from the apertures 8. The cotter pins may then be placed in the holes 13 to prevent accidental displacement of the released tension pins. The tension pins may then be rotated by any convenient tool such as a wrench to cause the wires 15 of the fence to wind thereabout as shown in Fig. 3. By turning the tension pins 9, the wires 15 of the fence are wound thereabout due to the locked engagement of the wires with said tension pins. In this manner, the wires of the fence may be stretched very tight with little exertion on the part of the attendant.

When this form of post is used intermediate the ends of a fence, the wires 15 constituting the fence, extend through holes 17 in the web 4. When the post is used as a corner post, the ends of the wires 15 may be wound about the tension pins 9 and locked properly to enable the wires 15 of the fence to be properly wound about the same.

Minor changes may be resorted to in the commercial adaptation of my invention but,

What I claim as new is:

A fence post comprising a single member, U-shaped in cross section; spaced square openings in one of the sides of said mem-

ber; annular openings in the other side of said member, registering opposite said square openings; wire openings in the central portion of said member; tension pins 5 operating in said oppositely registering openings; each of said tension pins provided with a head at one end and a square shoulder adjacent said head, each shoulder being adapted to fit its said square opening; 10 the body portion of said pins being round and adapted to fit its said annular opening;

the free end of said pins being provided with transverse openings spaced apart slightly greater than the length of said shoulder and a cotter pin adapted to be fitted into the 15 inner of said openings to retain said shoulder in its said square opening and into the outer of said openings to retain said pin from full disengagement from said member when said pin is partially pulled out. 20

In testimony whereof, I affix my signature.
HARRY LINDENSMITH.
